CLAIM

The ornamental design for a computer keyboard support frame, as shown and described.

DESCRIPTION

FIG. 1 is a perspective view of a computer keyboard support frame in accordance with the present invention.

FIG. 2 is a disassembled perspective view;

FIG. 3 is a side view the opposite side being a mirror image thereof;

FIG. 4 is a front view;

FIG. 5 is a top view; and,

FIG. 6 is a bottom view thereof.

The hatching shown in FIG. 1 is understood to continue over the indicated surfaces and is also understood to represent a conventional material.
